UNITED STATES PATENT OFFICE

2,326,245

WALL FOR BUILDINGS

Raymond Nichols, Pittsburgh, and John A. Desmone, Springdale, Pa., assignors to Pittsburgh Corning Corporation, a corporation of Pennsylvania

Application October 26, 1940, Serial No. 362,962

10 Claims. (Cl. 72—42)

The present invention relates to wall structures and it has particular relation to a wall structure composed of hollow glass blocks.

The object of the invention is to provide a wall structure of the foregoing type which can be taken down or disassembled without damage to the blocks employed in construction.

A second object is to provide such construction in which portions can be removed or replaced at will to provide door or window openings and without disturbing the remaining portions of the structure.

These and other objects of the invention will be apparent from consideration of the following specification and the appended claims.

A need has heretofore existed for a method of securing or mounting glass blocks in a building wall and particularly in partition walls within a building in such manner as to admit of changes, such as the insertion or replacement of doors or windows in the wall without damaging the remaining portions of the wall and without damage to the blocks which are removed or shifted from one location to another. The problem has never heretofore been satisfactorily solved.

In accordance with the provisions of the present invention it is proposed to fabricate building walls, such as partitions and the like from glass blocks secured or mounted to provide a series of readily removable panels which can be taken out of the wall or replaced to form or to fill an opening without disturbing the mounting of the adjacent panels.

For a better understanding of the invention reference may now be had to the accompanying drawings in which like numerals refer to like parts throughout.

In the drawings

Figure 1 illustrates a building wall fabricated of panels of glass blocks in accordance with the provisions of the present invention.

Figure 2 is an elevational view showing the same wall with one of the panels removed and a conventional door structure inserted therein.

Figure 3 is a fragmentary sectional view taken substantially upon the line III—III of Figure 2.

Figure 4 is a fragmentary sectional view substantially upon the line IV—IV of Figure 2.

Figure 5 is a fragmentary sectional view substantially upon the line V—V of Figure 2.

Figure 6 is a fragmentary sectional view taken substantially upon the line VI—VI of Figure 2.

Figure 7 is a fragmentary isometric view of a frame element for one of the panels constituting the subject matter of the invention.

Figure 8 is a detailed isometric view of a key suitable for securing the panels together to provide a rigid wall.

Figure 9 is a fragmentary detail view, partly in section and partly in elevation of a system for securing a lintel structure at the top of a wall.

Figure 10 is a fragmentary view partly in elevation and partly in section of a system for securing the top of a door or window jamb to the lintel.

Figure 11 is a sectional view taken substantially upon the line XI—XI of Figure 10.

Figure 12 is a fragmentary sectional view on the line XII—XII of Figure 5 showing a preferred method of mounting the blocks.

Figure 13 is a further form of jamb structure embodying the invention.

A wall constructed in accordance with the provisions of the present invention comprises hollow glass blocks 13, which may be of conventional design. These blocks are arranged in vertical columns 13a with horizontal courses 13b. The courses above are supported upon those in the courses below, after the manner of blocks in a masonry or brick wall. The blocks may be bonded together by any convenient means, for example, by means of mortar or cement disposed between the edges of contiguous blocks. However, a preferred construction comprises locking bars or strips (shown in Fig. 12), which may be of bronze, stainless steel, aluminum or any other convenient strong and durable material. A suitable form of the mounting strip is disclosed in the patent to Hohl No. 2,141,000, patented as of December 20, 1938. A construction of this type includes horizontal strips 14, which preferably extend the entire width of the panel and vertical strips 15, which preferably extend from one horizontal bar or strip to the next.

Each panel of blocks is disposed in a frame or chase structure of so-called perimeter stock or strip which includes vertical members 16 shown in Figure 3 and horizontal members 17 of identical section shown in Figure 6. Each perimeter member preferably is of a strong and durable metal and may include an intermediate web portion 18 and marginal ribs or flanges 19 adapted to engage the marginal faces of the blocks 13. The strips may also include shoulders 21 having slots or channels 21a to receive the edge portions of cover or finishing plates 22.

A mounting, as shown in Figure 3, constituting a lintel, or alternatively for securing the first panel of the series to the contiguous portions of the building, which portion is indicated at 23, e. g. a wall or alternatively a ceiling, includes a

bar 24, which is secured to the portion 23 by suitable bolts or lag screws 26. Wooden fillers 27, also, are secured to contact the strip or bar 16 adjacent the edges with a marginal portion of each filler engaging the inner face of the adjacent lip 21. The fillers 27 at their opposite edges engage the sides 29 of the bar 24 and may be secured to the latter by screws 30, nails, or other suitable devices. Angle bars 31, having legs or branches 32, secured to wall 23 by means of screws or bolts 33, have branches 34 that engage the faces of the adjacent marginal portions of the fillers and receive screws 35 which function to secure the plates 22 to the fillers.

As further shown in Figure 3 and shown in greater detail in Figure 12, the horizontal bars 14 between vertical bars 15 may be provided with projecting lugs 36 adapted to extend through openings 31 in the vertical perimetric frame elements 16. These lugs are formed with openings 38 in which wedge-like keys 39 may be inserted in order positively to key the bars 14 in place and thus substantially to strengthen the construction by positively tying together the bars 17 upon opposite sides of the panels and enabling the strips to resist without distortion the pull of other frame elements attached thereto.

Suitable sill and lintel constructions for use with the assembly are shown in Figure 6 and may include for the sill, as shown in Fig. 1, sections joined as indicated at 40 and corresponding to the width of the panels. Each section comprises a channel-like bar 41 having upstanding spaced flanges 42 and a web 43, the latter of which rests upon the floor 44 of the building.

In order to anchor the bar securely to the floor openings 46 may be formed in the web portions 18 of bars 16 and locking plates or stirrup plates 47 are secured to the web to span the openings. These plates comprise end portions 48 which may be anchored to the web 18 by welding, by rivets or other convenient means and an intermediate loop portion 49 downwardly bent from the web and being provided with an opening 51. This opening receives a floor bolt 52 which preferably is inserted in position before the glass blocks 13 are laid up in the frame. The head 53 of the bolt is accessible for application of a socket wrench or other turning device by reason of its alignment with the opening 46 in the web 18. The side plates 54, to cover the upstanding flanges of the channel elements 41, is inserted at its upper edge in the slot in the shoulder 21 of lower bar 16 and is secured below the shoulder to the upstanding flanges 42, by means of rivets or bolts 56.

A lintel structure for the panel assembly includes a channel or chase 57 which is either formed in sections as indicated by dotted lines A in Fig. 10 or is continuous the entire width of the series of panels and has downwardly-directed flanges 58 and slots 59 formed in the flanges to receive the upper edge portions of decorative cover plates 61. Within the channel provided by the flanges 58 are disposed spaced wooden bars 62, held in place by screws 63. The bars have secured to the lower face thereof a channel 64 having spaced sides 65 and an interconnecting web 66. Connection between the channel and the bars is effected by means of screws 67 extending through suitable openings to web portion 66. The upper edge of the panel of glass blocks is also provided with one of the horizontal perimeter bars 17, identical in all respects to the bar described in connection with Figure 4 and

including a stirrup element 68 corresponding to the element 47. Between the web portion 66 and the stirrup plate 68 is disposed a connecting bolt 69 extending through an opening in the web and being threaded through opening 51 in the stirrup or being provided with a nut 70 threaded thereupon in such manner as to prevent displacement of the bolt from the opening. As will be observed the shoulders 21 of the upper bar 17 receive in a suitable slot the lower marginal portion of the cover plate 61, in order securely to hold the latter in position.

A suitable connection for maintaining the lintel structure in position in an opening is disclosed in Figure 9. In this construction the upper extremity of the bar 24 may be extended upwardly between the flanges 65 of the channel bar 64 in such manner as positively to prevent any lateral displacement of the bar. The weight of the lintel is usually sufficient to hold it in place, but if desired the flanges 65 and bar 24 may be bored to receive a bolt 71.

A mullion construction for interconnecting contiguous edges of a pair of panels is shown in Figure 4 and includes key or link elements 72, which as shown in Figure 8 may be in the form of bars of rectangular section having pairs of grooves 73 formed contiguous to the ends thereof and being adapted to drop into slots 74 formed in the stirrup plates 41, which thus constitute keepers for the keys upon the webs 18 of vertical perimeter bars 16. When the bars are juxtaposed to each other as shown in Figure 4 and the key elements are dropped into position, as shown, the bars are positively locked together. It will be apparent that the length of keys may be so selected as to permit any desired spacing between contiguous panels thus allowing for various widths of wall openings to be closed.

In order to provide a closure or filler for the space between the bars, wooden strips or blocks 75 are inserted between the bars with their inner faces engaging the loop portions 49 of the stirrup plates 47. These wooden bars or blocks are locked together by means of through bolts 76 having nuts 76a threaded thereupon, in order to admit of tightening the bars or blocks upon the loops 49.

Spring clips 77, which may comprise short sections or an elongated member extending substantially the full length of the mullion, may be secured to the blocks or bars 75, for example, by means of screws, and are provided with shoulder portions 78 adapted to engage with inwardly bent lips 79 of cover plates 81; the latter are secured in position by merely snapping the lip 79 into engagement with the lips or flanges 78, thus maintaining a frictional engagement which can be broken by prying on the cover plate with a screw driver or other suitable instrument, to give access to the nut 76, permitting the blocks or bars 75 to be removed. When the latter operation has been effected the keys 72 may, of course, be lifted out to release any desired bar 16 and permit its removal from the wall. The mullions need not be secured at their tops and bottoms, because they are adequately held by the edges of the glass block panels.

A door or window jamb construction suitable for use in connection with the construction described as shown in Figs. 5 and 12 includes a vertical channel element 82, having flanges 83 in spaced relation adapted to engage one of the vertical perimeter bars 16, of a desired panel and being secured to the bar by means of a bolt

84, threaded in the same manner as bolt 69 into the stirrup or locking plate 47.

A channel 86, identical with channel 57, is also disposed over the channel 82 and cover plates 87 are disposed with the marginal portions thereof in the grooves formed in the flanges 58 of the channel and within the grooves in the shoulders 21. If desired, a wooden filler bar 88 may be disposed within the channel 86 and wedge-like shims 89 may be disposed between the exposed face of the bar and the inner face of the channel 82. By proper adjustment of the shims the spacing between the jambs may be regulated. Screws 90, through channel 86 and threaded into channel 82, hold the former channel from displacement.

Angle elements 91 are secured to the outer faces of the channels 86 and have flanges 92 against which the marginal portions of a door panel 93 are adapted to abut when the door is in closed position. This door, as shown in Figure 5, may be of conventional construction and is supported upon a hinge 93a including leaves 94 and 96, which are pivotally connected as indicated at 97. Screws 98, threaded through leaf 96, angle 91 and into bar 88, hold the hinges upon the jamb.

The construction of the portion of the lintel bar over the door opening is shown in Figures 10 and 11. It includes a T-like bracket 101, one leg 102 of which is secured by bolts 103 to the web 66 of channel 64. The other leg 104 is secured by bolt 106 to a flange or tongue 107, constituting a projection of the web of channel 82. As shown in Fig. 5, in order to anchor the bottom of the jamb to the floor channel 82 is provided with an angle bracket 110 that may be fastened by bolts 111 to the floor, or otherwise secured. Bolts 112 extend through the web of channel 82 and through branch 113 of the angle to provide a rigid connection. A finish shown in Figs. 10 and 11 is provided along the lower side of the lintel over the door opening by a channel section 114, which is identical with channels 57 and 86. The grooves in the flanges of this channel receive the adjacent portions of the lower edges of cover plates 61. In order to secure and support this channel, it is provided upon its inner or upper face with stirrup or loop-like cross elements 116, which are identical with elements 47 and are bored and threaded to receive the lower extremities of bolts 69 from channel 64.

In a jamb structure, such as that shown in Fig. 13, a bar 120 is secured by nails or screws 121, to a wall surface 122. A pair or a plurality of pairs of oppositely pointed wedges 123 and 124 are disposed in overlapping relation against the surface of the bar and provide an adjustable bearing surface for the loop or stirrup 47 of an edge member 16. Screws 124 inserted through hole 51 in the stirrup maintain the latter from displacement. These screws may pass through the wedges or may be passed between vertically spaced pairs of wedges. Finish plates 126 are disposed with one edge in the groove 21a and having the other edge concealed by a molding 127, which may be secured to wall 122 by screws 128. The edges of glass blocks 129 are disposed in the channel between shoulders 19 of the member 16.

In the assembly of a wall from panels of glass blocks in accordance with the provisions of the present invention the frame structures of the panels may be assembled in position, the sill sec-

tions for example being assembled first and the jamb sections and mullions being erected at the joints between the sections. The glass blocks are laid up in position with the securing bars 14 and 15 between contiguous blocks. Or if preferred, the blocks may be simply secured together and sealed about their margins by means of a cement, such as Portland cement or the like. Finally the lintel across the top is assembled and lifted in position. Obviously sufficient space between the tops of the blocks and the ceiling must be left to allow its insertion. If it should be desired to carry the wall structure completely to the ceiling, the structure shown in Figure 3 may be employed as a lintel. In the latter case angles 101 holding the jamb structure shown in Figure 10 may be attached by screws to bar 24. The channel 82 of the jamb may then be secured to the bracket by bolt 106.

Assuming that it is desired to remove one of the panels and insert a door in the opening thus formed, the assembly with respect to the specific panel is merely reversed. The first operation preferably involves removal of the lintel across the tops of the panels. In event that the blocks are held together by means of the bars 14 and 15, the cover plates 81 of the mullion shown in Fig. 4 may be first removed to give access to the bolts 76 which can be removed to release the bars 75. When this is accomplished the keys 39 are accessible and can be removed to release the bars 14 and after the blocks have been taken from the panel key 12 may be removed and the framework of the panel including the entire section of the sill structure removed. The vertical perimeter bars or strips 16 of the neighboring panels adjacent to the opening of course are retained. As shown in Fig. 10 the channel 82 of the jamb may be bolted in place to angle brackets 101 and 110 and the bolts 64 are inserted therein and threaded into locking plates or stirrups 47 on the strip 16. The channel 86 shown in Fig. 5 constituting the facing of the jamb may be bolted by bolts 84 to the channel 82, channel 114 may be secured to channel 64 of the lintel beam and the latter is lifted into position on top of the wall. The bolts 103 are inserted in bracket 101 to secure the top of the jamb and the channel 57 is secured upon channel 64. The door stop angles 92 or other structures, such as window guides, may be secured in position and finally the door may be hung in position.

It will be evident that the panel removed may be wider than the opening desired for the door. In the latter case the excess space may be filled by a narrow panel 125, which is assembled and secured in place in the same manner as the panels already described. In event that it should become desirable to fill the door opening, the door jamb structure is simply removed and replaced by a frame structure for the panel. Subsequently the glass blocks can be laid in the place to fill the opening.

The assembly of the panels in situ upon the job has been described. However, it is also contemplated that it may be desirable to reassemble them in the perimeter bar frames at the factory or on the job, and then to move them into place as a unit. The mullion, jamb and other structures can then be applied to provide a complete wall.

The forms of the invention herein described and illustrated are to be considered merely as illustrative. It will be apparent to those skilled in the art that numerous modifications may be made

therein without departure from the spirit of the invention or the scope of the appended claims.

What we claim is:

1. A wall structure comprising a series of panels, each panel being composed of a plurality of glass blocks, the panels being provided with a frame of perimeter bars, the bars between adjacent edges of the panels being provided with stirrups comprising straps of metal and link-like key elements interconnecting the stirrups.

2. A wall structure comprising a series of panels, each panel being composed of a plurality of glass blocks, the panels being provided with a frame of perimeter bars, the bars between adjacent edges of the panels being provided with stirrups comprising straps of metal and link-like key elements interconnecting the stirrups, said stirrups having notches formed in an edge thereof and said key elements having locking portions fitting into the slots.

3. A wall structure comprising a series of panels of glass blocks, each panel being disposed in a frame including an upper perimeter bar, said bar having stirrups on the upper face thereof, a channel iron disposed with the flanges thereof facing downwardly above the perimeter bar and bolts extending through the web of the channel and through the stirrups and providing a connection between the perimeter bar and the channel.

4. A wall structure comprising a series of panels of glass blocks, each panel being disposed in a frame including an upper perimeter bar, said bar having stirrups on the upper face thereof, a channel iron disposed with the flanges thereof facing downwardly above the perimeter bar and bolts extending through the web of the channel and through the stirrups and providing a connection between the perimeter bar and the channel, the perimeter bar having upwardly-extending flanges, which flanges have grooves formed therein, a second channel disposed above the first-mentioned channel and having flanges with longitudinal grooves in the lower edges thereof extending downwardly and cover plates disposed in the grooves in the flanges upon said channel and upon said perimeter bar.

5. A jamb structure for a panel of glass blocks,

said structure comprising a vertical perimeter bar having stirrups connected to the outer face thereof, a channel bar disposed over the stirrups and bolts extending through the channel into the stirrups to hold the channel in place.

6. A jamb structure for a panel of glass blocks, said structure comprising a vertical perimeter bar having stirrups connected to the outer face thereof, a channel bar disposed over and having flanges directed toward the perimeter bar, the stirrups and bolts extending through the channel into the stirrups to hold the channel in place, a finishing channel over the first channel and a cover plate bridging between the flanges of the latter and the perimeter bar.

7. A wall comprising a panel of glass blocks, said panel having a bar disposed thereover, which bar comprises a lower channel-like element facing upwardly and having stirrups upon its upper face, a downwardly faced channel disposed above the first-mentioned channel and bolts extending through the second channel and into the stirrups upon the first.

8. A wall structure comprising a panel of glass blocks, said panel having perimeter bars disposed about the edges thereof, the perimeter bars having stirrups formed upon the exposed face thereof, bars about the panel and spaced from the perimeter bars and bolts interconnecting the bars spaced from the perimeter bars and the stirrups, the blocks having ties disposed therebetween and secured at opposite ends to the perimeter bars, to strengthen them against the pull exerted upon the stirrups.

9. A perimeter bar for a panel of glass blocks in a building wall, said bar comprising a web portion and marginal shoulders upon the face thereof, adapted to provide a base for an edge of the panel, an opening in the web, a stirrup spanning the opening and an opening in the stirrup adapted to receive a fastening element.

10. A perimeter bar as defined in claim 9, said bar being provided upon the back with shoulders adjacent the edges, the latter shoulders having grooves formed therein, adapted to receive the edges of finishing plates.

RAYMOND NICHOLS.
JOHN A. DESMONE.
